I claim the ornamental design for a multi-player slot machine, as shown and described.

DESCRIPTION

FIG. 1 is front perspective view of a first embodiment of a multi-player slot machine showing my new design;

FIG. 2 is a front view of the multi-player slot machine shown in FIG. 1;

FIG. 3 is a right side view of the multi-player slot machine shown in FIG. 1;

FIG. 4 is a left side view of the multi-player slot machine shown in FIG. 1;

FIG. 5 is a back view of the multi-player slot machine shown in FIG. 1;

FIG. 6 is a top view of the multi-player slot machine shown in FIG. 1;

FIG. 7 is front perspective view of a second embodiment of a multi-player slot machine showing my new design;

FIG. 8 is a front view of the multi-player slot machine shown in FIG. 7;

FIG. 9 is a right side view of the multi-player slot machine shown in FIG. 7;

FIG. 10 is a left side view of the multi-player slot machine shown in FIG. 7;

FIG. 11 is a back view of the multi-player slot machine shown in FIG. 7; and,

FIG. 12 is a top view of the multi-player slot machine shown in FIG. 7.

The broken line showing portions of the multi-player slot machine depicts environment and forms no part of the claim.
